UNITED STATES PATENT OFFICE.

EARLE H. GOWING, OF READING, MASSACHUSETTS.

FURNACE.

SPECIFICATION forming part of Letters Patent No. 700,036, dated May 13, 1902.

Application filed July 6, 1901. Serial No. 67,358. (No model.)

To all whom it may concern:

Be it known that I, EARLE H. GOWING, of Reading, in the county of Middlesex and State of Massachusetts, have invented certain new and useful Improvements in Furnaces, of which the following is a specification.

This invention has relation to furnaces of the type wherein the fuel is fed from beneath by an underfeed mechanical stoker, as shown in the patent to Barrus, No. 646,408, dated April 3, 1900. In the practical operation of such furnaces having a retort which extends across the back end of the furnace with twy whole mouth located along the front and rear of its mouth it has been found that most of the air is discharged through the coal in the immediate neighborhood of the twy whole and comparatively little is forced up through the solid body of fuel within and above the retort. The distribution of the air through the mass of burning coal is thus restricted, and consequently the steam-producing capacity of the boiler is likewise restricted. One reason for the lack of thorough distribution of air is the fact that the surface of the coal above the retort pitches forward by the law of gravitation, the depth of coal above the rear line of twy whole being much greater than the depth above the front row. The increased thickness along the rear prevents this part of the furnace from receiving a fair proportion of the air supplied, owing to the greater resistance of the fuel to the passage of said air. Hence to secure a thoroughly satisfactory distribution of the air, and consequently a wide range of capacity in the working of the boiler, is the object of the present invention.

Instead of placing the two rows of twy whole on the same level I provide a construction in which the rear line of twy whole is elevated a sufficient distance above the front line so that the thickness of coal lying above it is no greater than that over the front row, in which case the resistance offered to the passage of air through the fuel is no greater at one point than at the other.

Again, according to my invention I provide for the distribution of air over a larger area, which can be done in several ways. One method of securing the required distribution is to remove a number of the rectangular twy whole which form the straight

rows and put in their places projecting blocks—that is, twy whole which project into the retort a considerable distance—these being applied either in the front row or in the back row, or in both, the twy whole outlets being thus arranged so as to discharge the air farther into the mass of coal than can be accomplished with the simple straight row. With this arrangement the row of twy whole may take the form of a sinuous line instead of a straight line, being set upon alternate projections and indentations in the front and rear walls of the retort. Another method of providing for the better distribution of air is to increase the number of twy whole by providing one or more longitudinal air boxes or ducts connecting the front and rear boxes. These longitudinal air boxes or ducts extend across the retort from front to rear and are inclined upward from front to rear to receive the twy whole, which are placed upon their tops and which are provided with air-outlets on either side. These twy whole may extend either the whole distance across the retort, forming a continuous row of blocks, or one or more twy whole, either rectangular or circular, may be placed over the box between the front and rear rows.

Another arrangement is the extension of the longitudinal air box or duct any desired distance in front of the front air-box along the top of the dead-plates and the provision of twy whole located on the top of these extensions. The longitudinal air-boxes and the extensions to the same, as also the projecting twy whole, can be used either in connection with the front and rear transverse air-boxes placed at different elevations, in which case they are either inclined or stepped upward from front to rear, or in connection with the same when placed on the same level, in either case the object being to increase the area over which the air is distributed by the use of the twy whole.

From this brief description it will be seen that my invention consists in means for securing a thorough distribution of air through and among the burning coal in this type of mechanical stoker or any other mechanical stoker to which the coal is fed at the back of the furnace and in which consequently the burning fuel is inclined downward from rear

to front, so that the ashes and clinkers are deposited in the front of the furnace.

Referring to the accompanying drawings, Figure 1 is a vertical longitudinal section showing a mechanical stoker of the type referred to, having a row of transverse twyer-blocks at both the front and rear of the retort. Figs. 2 and 3 illustrate another embodiment of the invention. Figs. 4 and 5 illustrate 10 an embodiment of the invention in which the front row of twyer-blocks is provided with forwardly-projecting extensions. Figs. 6, 7, and 8 illustrate a system of air distribution in which the intermediate longitudinally-arranged twyer-blocks are interposed between the front and rear rows of blocks.

Referring more particularly to Fig. 1, the stoker here shown is represented as being applied to a water-tube boiler, but a small portion of which is illustrated. Said stoker comprises the dead-plates P and means for feeding the coal from beneath, as indicated in the said Barrus patent, to the magazine, which extends across the rear end of the furnace.

25 a represents the front air-box, and b the rear air-box, connected together at the ends by ducts (shown in dotted lines) and supplied with air under pressure from the front through the channel c. The air passes from the top of the air-boxes through openings into the bottom of the hollow twyer-blocks and from this point emerges into the body of the coal through the lateral openings d. The twyer-blocks e in the rear row are placed at a higher elevation than the blocks f in the front row, the increased height of the blocks e above the blocks f being such as to conform to the natural slope of the surface of the coal which is fed up through the retort. This increase in 40 height requires to be eight inches, or thereabout, to secure the desired equality of air-distribution, although this height depends somewhat upon the character of the coal which is used and somewhat upon the width 45 of the retort or distance of the two lines of twyers from each other.

The front air-box a and the rear air-box b are connected by wings or ducts at the end of the retort, as previously explained. In place 50 of some of the twyer-blocks, which would otherwise be in the straight row, either at the front or rear, there are projecting twyer-blocks g. As here represented, every third block is a projecting twyer, and the intermediate ones occupy substantially the original location. If preferred, they may be placed at any other distance apart as may be found most desirable. They may be inclined, as the blocks e are shown, or stepped or level, 55 as may be preferred, and they may be placed alternately at the front and rear, as shown, or opposite each other. In the projecting blocks the air-outlets h may be located on the face of the block in the same relative position with reference to the body of the block as in those placed in the straight row, or they 60 may be located in both the sides and face, as

shown in the blocks e in Fig. 3. Instead of the arrangement of the air-boxes shown in the drawings, which are the same as those 70 shown in Fig. 1, the top of the air-box, both front and rear, may be arranged in sinuous form and the projecting twyer located on the projecting part.

A modified arrangement of the projecting 75 twyers is shown in Figs. 4 and 5. The projections i here extend from the front row of twyer-blocks forward toward the front portion of the furnace as far as may be desired, these being provided with side outlets for the 80 discharge of air. This arrangement may be used either in place of that shown in Figs. 2 and 3 or in combination therewith, as preferred, or it may be used without the rear air-box and rear twyer-blocks, if it is desired 85 to dispense with them.

In Figs. 6, 7, and 8 I have shown an arrangement of retort and twyers in which the front and rear air-box is connected at various points by longitudinal boxes or channels 90 j, surmounted by twyer-blocks m, the transverse air-boxes a and b being the same as those shown in Fig. 1. The longitudinal air-box j, which extends from the front box to the rear box and the twyers above, is in line 95 with corresponding twyer-blocks at the two ends in the front and rear rows. In these figures the longitudinal box takes the place of every third twyer, the distance between two consecutive boxes being the width of two 100 blocks. I do not confine myself, however, to this number, as the longitudinal blocks may be introduced at every alternate space or at greater distances than shown in the drawings, as may be found desirable. To enable the 105 coal to pass up from the body of the retort without undue resistance, the bottom of the fore-and-aft box is made tapering, as shown at k in the cross-section, Fig. 8. This section also shows the location of the outlets of 110 the twyer, which are placed on each side near the top. These blocks can be arranged either with straight inclined tops, making a smooth surface, as shown, or they can be arranged so as to form a series of horizontal steps, as 115 may be preferred. I do not confine myself in this case to the use of a continuous row of individual blocks located on the longitudinal box, but these can be arranged with spaces between them, placing, if desired, a single 120 one in the center, or any number desired, with intermediate spaces. These can be made rectangular with side outlets n or with both side outlets and rear outlets, or they may be made 125 circular with outlets encircling the entire circumference or only a portion of the circumference.

As an equivalent of the arrangement of longitudinal twyer-blocks shown in Figs. 6, 7, and 8 these blocks may be extended forward from the front of the transverse air-box toward the front portion of the furnace as far as may be desired and the air-outlets continued on the side as far as the block ex-

tends. In case small individual blocks are used these may be placed on the top of the extension of the air-box toward the front, and they may form a continuous row, or they may consist of individual blocks, either rectangular or circular, separated by spaces, the same as those referred to for the fore- and-aft twyters. Either of these arrangements of longitudinal twyter-blocks or projecting twyters referred to can be applied to a retort having front and rear air-boxes on the same level; and I do not confine myself solely to their use on an incline, as specially illustrated in the drawings. Furthermore, it is not essential, even if inclined, that they should be arranged with a uniform incline, for, if found desirable, they may be placed so that the upper surfaces may conform to the natural slope which the coal assumes in being discharged from the retort into the furnace.

I do not confine myself in my invention to the exact combinations of projecting twyters, longitudinal twyters, and transverse twyters referred to or as illustrated in the drawings, for they may be arranged in other ways, and I desire to use any combination of the devices referred to which may accomplish the objects sought in substantially the same manner. I do not confine myself to the use of the longitudinal twyters and the projecting twyters in combination with the two transverse rows of twyters alone, as the row of twyters at the rear of the retort may be omitted altogether and the air supplied to the longitudinal and projecting twyters through the front box, these being arranged either with a level or an inclined or an irregular surface, as may be preferred.

I claim—

1. In an underfeed mechanical stoker in which the coal is supplied to a magazine or retort extending transversely across the rear

end of the furnace, a plurality of twyters extending transversely of the furnace and rising one above the other from the front to the rear of the furnace.

2. In an underfeed mechanical stoker in which the coal is supplied to a magazine or retort extending transversely across the rear end of the furnace, one or more rows of twyters transverse to said furnace, said row or rows including a plurality of twyters projecting beyond the remainder of the twyters in the said row or rows, so as to produce a more thorough distribution of the air throughout the fuel and above the retort.

3. In an underfeed mechanical stoker in which the coal is supplied to a magazine or retort extending transversely across the rear end of the furnace, a front air-box to which the air is supplied under pressure, a row of twyters connected to said box, and having one or more projecting twyters, so as to produce a thorough distribution of the air throughout the fuel.

4. In an underfeed mechanical stoker in which the coal is supplied to a magazine or retort extending transversely across the rear end of the furnace, a front air-box and a rear air-box to which the air is supplied under pressure, rows of twyters surmounting said boxes, one or more longitudinal air-boxes connecting the two first-mentioned boxes, and one or more twyter-blocks surmounting said longitudinal air box or boxes and having air-outlets, substantially as described.

In testimony whereof I have affixed my signature in presence of two witnesses.

EARLE H. GOWING.
